UNITED STATES PATENT OFFICE.

FRANCIS LANE MERRITT, OF LONDON, ENGLAND, ASSIGNOR OF THREE-EIGHTHS TO HENRY ARTHUR NAISMITH, OF CROYDON, ENGLAND.

INTERNAL-COMBUSTION ENGINE.

SPECIFICATION forming part of Letters Patent No. 605,583, dated June 14, 1898.

Application filed March 12, 1897. Serial No. 627,208. (No model.) Patented in England July 6, 1896, No. 14,959.

To all whom it may concern:

Be it known that I, FRANCIS LANE MERRITT, a subject of the Queen of the United Kingdom of Great Britain and Ireland, residing at No. 96 Loftus road, Shepherds Bush, London, England, have invented certain new and useful Improvements in Internal-Combustion Engines, (for which I have obtained a patent in Great Britain and Ireland, No. 14,959, dated July 6, 1896;) and I do hereby declare that the following is a full, clear, and exact description of the invention, reference being made to the accompanying drawings, which are to be taken as part of this specification and read therewith, and one which will enable others skilled in the art to which it appertains to make and use the same.

The present invention relates to improvements in internal-combustion engines. It is applicable more particularly and with the best results to multi-cylinder engines. According to it an engine, whether single or double acting, works on an improved two-stroke cycle, the exhaust-gases are flushed out of the cylinder by improved means, the cylinder is cooled by improved means, and both the valve mechanism and the connection between the governor and it are improved in respect of both simplicity and invention.

Referring to the accompanying drawings, Figure 1 is a side elevation of a three-cylinder engine made according to the present invention. Fig. 2 is an end elevation corresponding therewith. Fig. 3 is a sectional side elevation taken along the line 3 3 of Fig. 2. Fig. 4 is a sectional end elevation taken along the line 4 4 of Fig. 3. Fig. 5 is a detail in transverse section of the cam mechanism by which the supply-valves are actuated. Fig. 6 is a front elevation corresponding therewith. Fig. 7 is a side elevation of the device by which the cam is held to the engine-shaft. Fig. 8 is a sectional side elevation taken along the line 8 8 of Fig. 4, but showing the air compressed in a different position. Fig. 9 is a detail of the contacts and contact-ring of the igniting mechanism. Fig. 10 is an elevation of the opposite side of the contact-ring. Fig. 11 is a plan of the said ring.

I have chosen for illustration a single-act-

ing three-cylinder engine having its cylinders standing with their axes set at equal angles about and radial to a common center situate in the axis of the engine crank-shaft, for the reason that the absence of vibration in the engine as a whole, due to the fact that the impulses are delivered to the crank-pins in regular order, specially adapts such a type of engine for use where vibration is inadmissible, as in the engine of a horseless carriage or motor-car. At the same time it must be explained that my invention does not relate to the type of engine nor to the number of cylinders, for the reason that it is applicable to either single or multiple cylinders having linearly-reciprocating and single or double acting pistons.

To prevent confusion of ideas, the term "stroke" is to be understood as meaning one travel of the piston from one end of the cylinder to the other. The engine works on a two-stroke cycle. During one stroke the exhaust-gases are flushed out of the cylinder, the exhaust-port is closed, the charge of air and combustible fed, into the cylinder, and the compression of it effected. During the following stroke the charge is ignited, work done on the piston, and the exhaust-port opened.

A A A are the engine-cylinders, and A' A' A' the pistons.

b is a central ring, to which the cylinders are made fast by their inner ends, the latter being received in sockets a' a' a', which project radially outwardly from the said ring.

d d' are two plates respectively held up to and over the edges of the ring b and forming with it a casing which incloses a portion of the crank-shaft, the crank, and the pitmen. This casing is hereinafter referred to as the "crank-chamber."

e is one arm of the crank-shaft. It has its bearings in a boss b', which projects centrally from the plate d into the crank-chamber. It is continued beyond that bearing outward far enough to carry the cam mechanism and inward far enough for the adjacent crank-cheek c to be made fast to it. e' is the other arm of the crank. It has its bearing in a boss b', which projects centrally from the plate d'.

into the crank-chamber. It is continued beyond that bearing into the crank-chamber far enough for the adjacent crank-cheek c' to be made fast to it. Both cheeks c c' are circular, of the same diameter as the interior of the crank-chamber, and are revolved upon the respective bosses b' b^2 .

a^3 a^3 a^3 are the pitmen.

a^2 is the single crank-pin, to which all the pitmen are connected. It turns in bearings in the cheeks c c' . The ends of the pitmen are held to it by being shaped to the same radius, by having a width rather less than a third of a circle, and by having their ends entered into bearings in the cheeks c c' , such bearings being of course concentric with those of the crank-pin a^2 .

F is a ring of about the same diameter as the ring b . It fits over the plate d' and up to the said ring. f is a third circular plate. It is held over and up to the edge of the ring F . This latter, together with the plates d' and f , forms the chamber of the air-compressor, described farther on. The rings b and F and the plates d , d' , and f are shown as held to each other in the respective positions described by screw-threaded and nutted tie-bolts d^2 . The crank-shaft arm is continued through the air-compressor chamber, the outer end of such continuation e^3 turning in a bearing e^4 , formed in the circular plate f .

The function of the air-compressor is to supply the engine with air for combustion, as well as with air-currents for cooling the cylinders and flushing the exhaust-gases out of them, both such supply and currents being under pressure. It consists of a radial arm f' , air-supply ports f^2 f^3 , and blades f^4 .

The radial arm f' is fast upon the continuation e^2 , above mentioned, that being the compressor-shaft. The said arm extends outward and laterally as far as the internal face of the compressor-chamber, up to which it fits air-tight on all three sides of it. The outer end of this arm, being the one always in contact with the periphery of the said chamber, is preferably convex. The sides and opposite end of it must be convex to provide for the tips of the blades f^4 riding over them smoothly—i. e., without jumping away from them.

The air-port f^2 is open to the outer air through the outer end of the shaft e^3 and extends throughout the length of the latter, making it tubular or hollow.

f^3 f^3 are a series of parallel ducts starting from the air-port f^2 , extending through the arm f' , and opening out through one side or through one end of it, their mouths being so positioned as to open into only one of the sub-chambers at a time. These subchambers are described farther on. Each series of ducts f^3 is functionally a continuation of the port f^2 . As the compressor-shaft e^3 is constantly revolving, the action of the compressor itself is constant.

The blades f^4 are counterparts of each other. There are as many of them as there are cylinders in the engine, making that number of subchambers. Each is pivoted by its base, 70 either to the sides or to the periphery of the compressor-casing, the axis of such pivot being parallel with the axis of the compressor itself. There is formed in the drum f a recess f^5 of a proper size to receive each blade 75 as the outer end or tip of the arm f' travels past, the adjacent face of a blade being of the proper contour to complete the internal surface of the drum F over each recess f^5 . Fig. 8 indicates the pivot of a blade as consisting of a gudgeon f^6 , projecting from each corner into a bearing in the side of the compressor-chamber out of the path of the tip of the arm f' .

f^8 f^8 f^8 are channels in the ring F , one to 85 each subchamber and open, respectively, to the recesses f^5 . They are continued through the ring b as closed ports f^9 and not open to the crank-shaft chamber. The tips of the blades f^4 are kept in contact with the surface of the arm f' by any suitable spring device. By preference I use a resilient spring contained in sliding thimbles to act on the back of blades f^4 , maintaining constant contact with arm f' . This device is illustrated 95 in Fig. 8.

p is a spiral spring resilient between the opposite ends of two cups p' p^2 . The cup p' is held by its edge to the ring F , the closed end or bottom of the cup projecting radially 100 therefrom. The cup p^2 is small enough to slide radially within the cup p' , the spring p being strong enough to keep the closed end of the cup p^2 constantly in touch with the respective blade f^4 , while the cup p' is long 105 enough to receive the entire length of the cup p^2 .

The tips of the blades f^4 being kept in contact with the surface of the arm f' and the motion of the latter being constant in the direction indicated by the arrow—i. e., from tip to pivot of a blade—the air in a subchamber is expelled therefrom by the circular motion of the arm f' folding the respective blade into its recess and forced through the channels f^8 115 and the continuations f^9 thereof in the ring b on its way to the chamber g^4 , described farther on.

Each cylinder, with its valve-gear, is a replica of each of the others. A description of 120 one is for that reason a description of all.

g is an annular chamber which jackets the cylinder A . One end of the shell g' of it fits over a shoulder on the ring b and is held in position concentric with the cylinder by the 125 cover H of the outer end of the latter and studs h .

g^2 is one of a series of ports from each port f^9 to the chamber g , and g^3 g^3 a series of ports in the cylinder-cover H from the said chamber g' into one g^4 , situated within the said cover H . It is the combination of the cham-

bers g g^4 with the ports g^2 g^3 which provides for the access of air to the cylinder for both combustion and for flushing, while the constant action of the air-compressor maintains a sufficient supply at the necessary pressure.

The position of the ports g^2 is deserving of notice. The diameters of the crank-shaft chamber and of the air-compressor chamber are practically identical, and the two standing end to end present the appearance of a single continuous one. The shells g' of the chambers g intersect (in the language of geometrical projection) the ring b , making internal right angles therewith. It is behind this internal angle that the ports g^2 stand, and consequently do not make any break in the periphery of either chamber or in that of the shell.

i is the main pipe, through which the combustible is supplied under suitable pressure, and i the branch from it to each cylinder. A branch i enters an axial prolongation h^4 of the end cover H and delivers the combustible into a small cylinder h' through the side of it and near the bottom of it.

h^2 is a piston-valve fitting the cylinder h' . The outer end of this valve is expanded laterally, and a resilient spring h^3 is inserted between such expansion and an external collar h^4 on the prolongation h , the function of it being to keep the valve h^2 away from the bottom of the small cylinder h' , thereby opening the port from the branch i and keeping it open.

J is the engine-supply valve. Its function is to control the supply of combustible and air for combustion to the cylinder A . j is its seating in the inner face of the end cover H . j' is the spindle of it. It works through the continuation h and the piston-valve h^2 , through both of which it is continued outwardly to terminate in a head j^3 , which stands normally a short distance off the outer end of the piston-valve h^2 and always in contact with the valve-actuating gear.

j^4 is a resilient spiral spring round the spindle j' and acting between the valve h^2 and the head j^3 .

j^5 is a tubular port in the spindle j' and having lateral branches j^6 , adapted to communicate with the bottom of the cylinder h' , and other lateral branches j^7 , adapted to communicate with the engine-cylinder A when the port from the branch i is covered by the piston-valve h^2 .

K is the engine-governor, and k the cam of the supply-valve-actuating gear. This cam is held and actuated on the shaft-arm e by the following means:

k' is a collar having a feather k^2 along one side of it. It is held to the shaft-arm e by a set-screw k^3 . Over this collar there fits a wedge-block. Its operative surfaces are, for the purposes of the present invention, a pair of wedges k^4 k^5 . These are on the outer surface of the wedge-block, opposite each other, at the same angle with the axis of the arm e and parallel with each other. The wedges k^4

k^5 are held on the arm e by the engagement of the feather k^2 in a corresponding slot in the inner surface of the wedge-block.

70

k^6 is a sleeve free to move along the arm e outward under the centrifugal action of the governor and inward under the extension of the spring k^7 .

k^8 k^9 are a pair of rods holding the wedge-block to the sleeve k^6 .

k^9 is the cam-block. It fits over and up to the periphery of the wedge-block, so that each longitudinal motion of the latter becomes a transverse one in the cam.

80

k^{10} is the cam-tooth. The exact position of this on the periphery of its block k^9 may be varied as may be desired. Both are prevented from moving longitudinally along the arm e by a cup k^{11} , fast to the said arm on each side of them.

l is the valve-rod working through the guide l' on the plate d . Its inner end carries an antifriction-roller l^2 always in contact with the periphery of the cam-block k . It reaches the valve J through a bell-crank lever l^3 , one end of which and the adjacent end of the valve-rod are pivotally connected, while the opposite end of the said bell-crank lever is in constant contact with the head j^3 of the valve-spindle j' .

90

The mechanism for igniting the charge of mixed combustible and air in the cylinder is electrical. A ring having half the width of its periphery a conductor m and the other half a non-conductor m' , excepting a single tooth m^2 of conducting material, is fixed upon the crank-shaft outside the chamber of the latter. It is carefully insulated. The two rings stand side by side. An incandescent igniter is fixed inside each cylinder. This is not shown in the drawings. Any one of those known may be used.

100

m^3 is the positive conductor from the battery to a contact-finger m^4 , which always bears upon the half-periphery m .

m^5 m^6 m^7 are the contact-fingers always in contact with the other half-periphery m' m^2 .

m^8 is the conductor from each finger m^5 to the positive binding-screw m^7 of the internal incandescent igniter, and m^9 the negative binding-screw thereof, from which the negative conductor m^9 is led away to the battery. The tooth m^2 therefore closes the three igniting-circuits in due order once during each rotation of the crank-shaft.

110

n is the exhaust-port. It is opened to the ignited and expanded charge of air and combustible at a suitable point in the working stroke of the piston A' .

120

n' is the exhaust-pipe.

The operation of the engine will be understood from a description of what goes on in and in connection with one cylinder.

130

When the piston A' is at the end of its inward or working stroke—i. e., in the position illustrated in Fig. 4—the exhaust-port n is full open. The piston then begins its return stroke. At the moment when it has covered

half the port n the cam-tooth k^10 comes up to the antifriction-roller l^2 and pushes the valve J a little way off its seat. The air-compressor then drives a cooling and flushing charge of 5 air through the ports g^2 , the jacket g , the ports g^3 , and the chamber g^4 , past the valve J , through the cylinder A , and out through the port n , cooling the cylinder A as it passes through the jacket g and flushing it of the 10 exhaust-gases, which latter it drives out through the exhaust-port n . All this cooling and flushing is accomplished while the port n remains open. By the time the piston A' has quite 15 covered the port n the same cam-tooth has opened the valve J a little farther, far enough, in fact, to push the branch ports j^6 past the end of the piston-valve h^2 . At this point is begun the admission of combustible from the small cylinder h' . It flows or is driven thence 20 through the ports j^6, j^5 , and j^7 into the cylinder A , where it is mixed with air from the air-compressor as the combustible passes out of the valve J . The air is induced or driven forward for the chamber g^4 into the cylinder 25 A by the currents of air forced forward by the compressor from the compressor. The cam-tooth now makes the piston-valve h^2 shut off the small cylinder h' and the ports j^6 from the valve h^2 and branch i by means of the 30 continued inward motion of the spindle-head j^3 and valve h^2 . As soon as the cam-tooth has passed the roller l^2 the spring h^3 returns the piston-valve h^2 , and the spring h^4 closes the valve J . The piston A' then begins to 35 compress the charge. As soon as it has started on its inward—i. e., working—stroke the circuit is closed and the charge fired. At that moment the inward stroke becomes the working stroke, and this continues to almost the 40 end of the inward stroke—at any rate, till after the piston has partially opened the exhaust-port n .

The independent action of which the piston-valve h^2 and the valve J are capable is an important feature of the present invention, for 45 by means of it, when the governor-holes are wide open, the projection of the cam-tooth will be so diminished that the ports j^6, j^5, j^7 will not be opened to the combustible-supply i .

50 I claim—

1. The combination in an internal-combustion engine working on the two-stroke cycle specified of working cylinder, a combustible-supply port, a piston-valve therein normally held from closing the said supply-port, a valve-controlled supply-port to the working cylinder, a single valve J normally holding the said supply-port closed, a port through the said valve adapted to establish communication between 55 the combustible-supply cylinder and the working cylinder when the single valve is off its seat, an air-supply to the working cylinder, a cam-tooth making one revolution for each two-stroke cycles of the engine and 60 adapted by intermediate valve-gear to push the single supply-valve off its seat a little to make the piston-valve close the combustible-

supply port, then to establish the above-mentioned communication between the combustible-supply cylinder and the working cylinder, 70 to leave the supply-valve to be closed, and to leave the piston-valve to open the combustible-supply port.

2. The combination of a centrifugal governor on a crank-shaft arm, a fixed sleeve 75 thereon, two inclosing cups fixed thereto, a double inclined block inclosed inside the said cups and protected by same to stop the block at each end of its transverse motion, a double inclined wedge-block mounted on a fixed 80 sleeve and giving it motion connected to governor through the said cups by rods giving longitudinal motion and a cam on the double inclined block, a double inclined block inclosed between two cups and to a fixed sleeve 85 having its longitudinal motion from the governor and transmitting the same to the cam which is also held between the edges of the said two cups to prevent a longitudinal motion to the said cam, a cam-block carried by 90 and rotating with the crank-shaft and held by the said cups that each longitudinal motion of the wedge-block becomes a transverse one in the cam, an antifriction-roller and valve-gear transmitting the motion of the cam 95 to the single supply-valve of the engine as described.

3. The combination of a centrifugal governor, a cam-tooth of variable projection under the action of the same, a valve-gear actuated by the said tooth, a valve controlling the only supply-port to the working cylinder adapted to be opened first by a given projection of the said tooth and a piston-valve controlling the combustible-supply to an intermediate cylinder adapted to be opened only by a longer projection of the said tooth.

4. The combination of a compressor (consisting of radial arm, air-supply ports and blades) mounted on the engine-shaft and capable of being subdivided into as many sub-chambers as there are cylinders to the engine, with as many ducts therefrom as there are subdivisions, a radial arm mounted on the said shaft inside a surrounding shell of a compressor revolving concentric to the same, an air-duct concentric to and in the axial line of the said shaft from the outside air to a series of air-ducts diverging outward from the said shaft and through the radial arm delivering its air into the compressor on the reverse side of the said arm's line of motion filling the vacuum caused by the forward motion, as many blades as there are subdivisions, each blade constructed to maintain a constant sliding contact with the radial arm, air-tight and to deliver its air to its own working cylinder through its own air-duct up to a supply-port and valve in each working cylinder, a casing suitably constructed according to the number of subdivisions, with recesses to receive the blades so that the radial arm may ride smoothly over them, and a return-spring to maintain air-tight contact between the 110 115 120 125 130

blades and the radial arm, a radial arm constructed of such a form that the blade may rise very quickly and deliver its air, the return motion being regulated by the outline 5 of the said arm to produce a smooth action, the function of the compressor being to supply the engine with air for combustion and air-currents for the various operations of the engine when working, both such supply and 10 currents being under pressure.

5. The combination in an internal-combustion engine working on the two-stroke cycle specified, of working cylinder, a constant and independent air-compressor, single valve 15 controlling the only supply-port to the said

cylinder, a piston-valve-controlling the combustible-supply port to an intermediate chamber, a valve-gear actuated by a single-tooth cam and opening the only single supply-valve to the cylinder according to the projection of 20 the said cam, and an automatic igniting device.

In witness whereof I have hereunto affixed my signature, in presence of two witnesses, this 16th day of February, 1897.

FRANCIS LANE MERRITT.
